DIAL TELEPHONE FINGER WHEEL

Joseph A. Petrel, Troy, N. Y.

Application December 14, 1932, Serial No. 647,253

5 Claims. (Cl. 179—90)

This invention relates to dial telephone finger wheels, and has, among its objects, the provision of a finger wheel permitting ready cleaning and greater visibility of, the telephone dial. The standard finger wheel for dial telephones is so constructed in itself and so related to the dial under it that the dial may be cleaned only with difficulty. It is known to users of dial telephones that the dial needs rather frequent cleaning due to the fact that it gathers dust and is also marked by pencils and by the fingers. The construction which I have provided allows quick cleaning of the dial. Furthermore, my invention permits a better view of the telephone dial or numeral-plate.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

In the drawing:

Fig. 1 is a side elevation of the dial and its mounting and also the finger wheel and the stop for the same.

Fig. 2 is a plan view of the apparatus shown in Fig. 1, and clearly shows one form in which the finger wheel of my invention may be constructed; and

Figs. 3 and 4 are plan views of finger wheels showing modified forms of my invention.

Referring to the drawing for a more detailed description thereof, and at first to Figs. 1 and 2, the dial 5 has the standard or any preferred indicia thereon, said indicia comprising numerals and letters, in groups. A finger wheel stop 6 is mounted on the side of the dial frame 8 and extends over and above the marginal portion of the finger wheel 9. Said wheel is shown as having the standard series of openings adjacent its periphery. As distinguished from the standard finger wheel, the wheel of my invention is shown in Fig. 2 as having an opening adjacent the stop 6 and between the digits "0" and "1" of the dial, said opening extending from the periphery of the wheel and being larger than the finger apertures used for operation of the wheel. It will be appreciated that such construction of

the finger wheel allows the dial to be readily cleaned and that it affords a better view of the dial while finger wheel is in motion.

Referring now to Fig. 3, an opening 10 is provided in the finger wheel 11 in a position similar to that described for Fig. 2. The opening 10 however does not extend to the periphery of the wheel, but being larger than the usual finger openings, affords sufficient space for conveniently cleaning the dial and clearer visibility.

Referring now to Fig. 4, the opening 12 may be described as the equivalent of the opening 10 of Fig. 3 extended to include the finger opening over the digit "0" of the dial, whereby a larger opening is provided without in any way interfering with the operation of the finger wheel.

The standard finger wheels on dial telephones are returned by a spring after turning movements by the subscriber. In the event that a spring breaks, the finger wheel may become wrongly adjusted making it at least very difficult for the subscriber to call a desired number. To overcome this difficulty, I have shown in Fig. 2, the finger wheel as having digits marked thereon corresponding to the digits on the dial and in similar positions.

I have also shown, in Fig. 2 and in Fig. 1 as well, a depending flange or apron 3a as part of the finger wheel, this for the purpose of preventing dirt from entering the working mechanism 30 below the wheel.

According to my invention, the finger wheel of a dial telephone has a reflecting surface in order to reflect light back onto the dial and therefore the better illuminate the latter. The reflecting surface may be obtained by plating the lower surface of the wheel or in any other suitable manner.

The wheel of my invention as shown in the drawing has less weight than the standard finger wheel now in use, and therefore is more easily returned by the spring, with the consequence that there is less wear on the spring.

It is well known that some subscribers desire at times to lock the finger wheel, and while the standard finger wheel now in use may be locked by means of an ordinary padlock, it is necessary to turn the finger wheel from its resting position in order to insert the ball of the lock through an aperture and around the finger stop. Using the finger wheel of my invention, as shown in Fig. 3, a lock 15 having a ball 16 may be employed to lock the wheel to the finger stop by passing the ball through the aperture 10 and the adjacent circular aperture and around the finger stop, this

without displacing the wheel from its resting position.

What is claimed is:

- 5 1. The combination with a number dial of a subscriber's telephone, which dial has a series of numbers arranged in a circular row throughout an arc of approximately 270° and spaced apart, a finger wheel rotatably mounted over said dial and having a series of finger openings, one for each dial number, through which openings the dial numbers are continuously visible, said finger wheel having an elongated recess in its periphery extending from adjacent the last finger opening to adjacent the first finger opening and of a depth 10 to expose the number carrying surface part of said dial as the wheel is rotated for the purpose of providing means to facilitate the cleaning of the number carrying portion of the dial, said recess being at all times exposed.
- 15 2. The combination with a number dial of a subscriber's telephone, which dial has a series of numbers arranged in a circular row throughout an arc of approximately 270° and spaced apart, a finger wheel rotatably mounted over said dial and having a series of finger openings, one for each dial number, through which openings the dial numbers are continuously visible, said finger wheel having an elongated recess in its periphery extending from adjacent the last finger opening to adjacent the first finger opening and of a depth 15 to expose the number carrying surface part of said dial as the wheel is rotated for the purpose of providing means to facilitate the cleaning of the number carrying portion of the dial, and to cooperate with the last finger opening to receive therewith the loop of a padlock to embrace the 20 finger stop of the telephone for locking the wheel in its stopped or normal position, the underside of said wheel being of light reflecting material and the exposed face of the wheel having thereon number digits formed on the wheel, one for each 25 hole and corresponding to the dial numbers.
- 25 3. The combination with a number dial of a subscriber's telephone, which dial has a series of numbers arranged in a circular row, throughout an arc of approximately 270° and spaced apart, a finger wheel rotatably mounted over said dial and having a series of finger openings, one for each dial number, through which openings the dial numbers are continuously visible, said finger wheel having an elongated recess in its periphery 30 extending from adjacent the last finger opening to adjacent the first finger opening and of a depth to expose the number carrying surface part of said dial as the wheel is rotated for the purpose of providing means to facilitate the cleaning of the number carrying portion of the dial, and to cooperate with the last finger opening to receive therewith the loop of a padlock to embrace the finger stop of the telephone for locking the wheel in its stopped or normal 35 position.
- 35 4. The combination with a number dial of a subscriber's telephone, which dial has a series of numbers arranged in a circular row, throughout an arc of approximately 270° and spaced apart, a finger wheel rotatably mounted over said dial and having a series of finger openings, one for each dial number, through which openings the dial numbers are continuously visible, said finger wheel having an elongated recess in its periphery 40 extending from adjacent the last finger opening to adjacent the first finger opening and of a depth to expose the number carrying surface part of said dial as the wheel is rotated for the purpose of providing means to facilitate the cleaning of the number carrying portion of the dial, and to cooperate with the last finger opening to receive therewith the loop of a padlock to embrace the finger stop of the telephone for locking the wheel in its stopped or normal 45 position.
- 45 5. The combination with a number dial of a subscriber's telephone, which dial has a series of numbers arranged in a circular row, throughout an arc of approximately 270° and spaced apart, a finger wheel rotatably mounted over said dial and having a series of finger openings, one for each dial number, through which openings the dial numbers are continuously visible, said finger wheel having an elongated recess in its periphery 50 extending from adjacent the last finger opening to adjacent the first finger opening and of a depth to expose the number carrying surface part of said dial as the wheel is rotated for the purpose of providing means to facilitate the cleaning of the number carrying portion of the dial, and to cooperate with the last finger opening to receive therewith the loop of a padlock to embrace the finger stop of the telephone for locking the wheel in its stopped or normal position.
